(57) **CLAIM**

I claim the ornamental design for an automated external defibrillator carry case, as shown and described.

DESCRIPTION

FIG. 1 is a front right perspective view of an automated external defibrillator carry case according to my design; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; and, FIG. 7 is a bottom view thereof.

Items shown in broken lines are for illustrative purposes only and form no part of the claimed invention.
